DEVICE FOR EXTERNALLY CLEANING OIL
WELL CASINGS AND PIPES

John J. Harrigan, Oklahoma City, Okla.

Application November 3, 1950, Serial No. 193,922

8 Claims. (Cl. 15—88)

1

This invention relates in general to certain new and useful improvements in power-driven devices for externally cleaning oil well casings and pipes and, more particularly, cleaning devices adapted for use in cleaning an oil-well casing as it is withdrawn from the drill hole in the process of well drilling operations.

It is the primary object of the present invention to provide a power-driven pipe cleaning device which is capable of cleaning the exterior surfaces of an oil-well casing as the casing is being removed from the drill hole.

It is another object of the present invention to provide a pipe cleaning brush of the type stated which may be readily employed with existing well drilling tools and equipment and can be readily adapted for installation upon power-driven pipe tongs or other similar pipe handling equipment ordinarily found at the location of well drilling operations.

It is an additional object of the present invention to provide a pipe cleaning brush which is simple and economical in construction and is rugged and durable in operation, so that it can be readily used under a wide variety of field conditions without requiring extraordinary training or skill on the part of the operator.

It is a further object of the present invention to provide a pipe cleaning device of the type stated which is economical in construction and is provided with brushing elements which can be discarded or replaced from time to time as may be required due to wear.

With the above and other objects in view, my invention resides in the novel features of form, construction, arrangement, and combination of parts presently described and pointed out in the claims.

In the accompanying drawings—

Figure 1 is a top plan view, partly broken away and in section, of a rotary casing brush constructed in accordance with and embodying the present invention;

Figure 2 is a side elevational view, partly broken away and in section, of a rotary casing brush;

Figure 3 is a fragmentary sectional view taken along line 3—3 of Figure 1;

Figure 4 is a perspective view of the brush element forming a part of the present invention;

Figures 5 and 6 are fragmentary sectional views showing the stabilizing rollers in operative and retracted positions, respectively;

Figure 7 is a fragmentary sectional view taken along line 7—7 of Figure 6;

2

Figures 8 and 9 are fragmentary sectional views taken along lines 8—8 and 9—9, respectively, of Figure 1; and

Figure 10 is a top plan view of the rotary tool equipped with a pipe gripping chuck by which it may be adapted for use as a pipe tong.

Referring now in more detail and by reference

characters to the drawings, which illustrate practical embodiments of the present invention, A 10 designates a power-driven pipe brushing tool comprising an outer shell or casing 1 formed by two horizontally spaced parallel plates 3, 4, peripherally secured together by walls 5, 6, and together extending radially outwardly in the provision of an elongated handle-like member 7. The arcuate side wall 5 is provided with an eye ring 8 which may be used for suspension of the device from a hook or other suitable instrumentality for manipulation into and out of position for actual use. Similarly, the other end of the handle 7 is provided with an eye-forming ring 9 which will serve also to provide means by which hooks or other manipulative elements may be attached to the tool A.

25 The housing 1 is provided in diametrically opposed relation to the handle 7 with a radially inwardly extending slot or throat 10 which is enlarged at its inner end to provide a concentric opening 11. Journaled at their upper and lower ends and extending vertically between the upper and lower plates 3, 4, and disposed in spaced annular relation around the inside of the housing 1 is a plurality of bearing spools 12 having diametrically enlarged, vertically spaced collars, 13, 13', which bear against the outer periphery of a ring gear 14 provided midway of its vertical height with a diametrically enlarged tooth section 15 which extends between the upper and lower collars 13, 13', of the spools 12. The ring gear 14 is provided with a radially inwardly extending slot 16 similar in size and shape to the slot 10. The slot 16 is enlarged in its inner end to provide a circular opening 17 substantially the same size as the circular concentric opening in the housing 1. It will thus be evident that when the ring gear 14 is brought to rest, so that the slot 16 is aligned with the slot 10 of the housing, it is possible to push the tool A around a section of pipe or casing, such as the casing shown at C in Figures 1 and 2, without uncoupling or disconnecting the casing, whereupon subsequent rotation of the ring gear 14 will enclose the pipe or casing C within the tool A.

Also journaled at its upper and lower ends in 50 and extending between the plates 3, 4, is a driv-

ing gear 18 which projects upwardly through the housing 1 and is connected to any suitable prime mover, such as the conventional air motor N as shown in Figure 2. It will, of course, be understood that a belt drive, connecting the gear 18 to an electric motor, or a conventional flexible shaft, connecting the gear 18 to any other source of power, may also be used, it being immaterial, so far as the present invention is concerned, what type of power may be used to drive the gear 18.

Also journaled vertically within the housing 1 in arcuately spaced relationship to the gear 18 and preferably equidistant on opposite sides thereof, are two idler gears 19, 19', said idler gears being mounted in slide blocks 20 which are shiftably biased by means of springs 21 away from the gear 18 for purposes presently more fully appearing. Disposed encirclingly around the gear 18 and the idler gears 19, 19', is an endless roller chain 22 which is in tight fitting engagement with the teeth of the ring gear 14 along the rearwardly presented segment, as shown in Figure 1. It will be noted in this connection that the position of the idler gears 19, 19', with respect to the gear 18 is such that the chain 22 will embrace the teeth of the ring gear 14 along approximately 45° of the arc and in any case a substantially greater distance than the width of the slot 16. Furthermore, the tension of the chain 22 against the teeth of the ring gear 14 will be maintained by the springs 21 which bias outwardly the slide blocks 20 in which the idler gears 19, 19', are mounted.

It will thus be seen that when the gear 18 is rotated by the air motor N, the chain will revolve the ring gear 14 and a sufficient number of teeth will be engaged at all times so that the gap caused by the slot 16 will be spanned and there will be no interruption in uniform application of driving power. Similarly, the slot 16 is somewhat smaller than the distance between any two adjacent spools, so that at all times during rotation the ring gear 14 will be held in true circular concentricity by engagement with all of the spools 12 or at least all spools 12 but one. In other words, the ring gear 14 is always held by at least seven out of the eight spools 12 shown.

The ring gear 14 is internally contoured to provide a pair of inwardly protruding tooth-like enlargements 23, 24, located on opposite sides of and adjacent to the slot 16 and a radially outwardly extending enlarged V-shaped recess 25 into which may be slipped a correspondingly shaped removable collar or chuck 26, the latter having a radially outwardly extending slot or mouth 27 adapted for coincident alignment with the slot 16 and a concentric enlarged opening 28 capable of freely embracing, but not engaging, a section of casing C. Mounted preferably at 60° intervals around the lower face of the collar or chuck 26 are depending L-shaped elements 29 which integrally include a horizontal flange 30 and a vertical leg 31. The horizontal flange 30 of each element 29 is provided with a pair of elongated apertures through which attachment bolts 32 may be inserted, thus providing for a limited degree of radial adjustment. The vertical leg members 31 are provided upon their inwardly presented faces with a plurality of bristles 33 in the formation of brushes b, which are adapted to impinge against the casing C and scour the mud, clay, and other undesirable material therefrom as the pipe or casing C is pulled upwardly out of the well hole.

The chuck 26 is substantially thicker than the housing 1 and projects upwardly therefrom so as to be accessible to the operator. In such upwardly projecting position, the chuck 26 is provided with three radial recesses 34 located at 60° intervals from each other and in vertical alignment with the brushes b. Each recess 34 is concentrically drilled in its bottom wall to provide an aperture 35 opening upon the outer or exposed face of the chuck 26 for slidably supporting the rod-like shank 36 of a plunger 37 formed integrally therewith and slidably fitting within the recess 34. At its forward end, the plunger is horizontally slotted for receiving a bearing roller 38 operatively held in place by a pin 39. Similarly, the outwardly projecting end of the forward two shanks 36, that is to say, the shanks 36 which are located on opposite sides of the throat 18, are slotted for receiving cam-headed handles 40 which bear against the outer face of the chuck 26. Disposed encirclingly about each shank 36 within the recesses 34 are springs 41 for resiliently urging the plungers radially inwardly into the pipe-embracing central opening 28. On the two shanks 36 which are provided with handles 40, the latter serve as limit-stops for the spring-biased action of the plungers 37 and the other shank 36, which is directly opposite the slot 27, is provided with a movement-limiting cotter-pin 42.

The chuck 26 is finally provided with a safety-link 43 permanently pivoted on one side of the slot 27 for optional disposition closurewise across the slot 27 and being provided at its free end 35 with an aperture 43' for receiving a wing-screw 44 which is removably threaded into the upper face of the chuck 26 on the other side of the slot 27.

When the device A is placed around a section 40 of pipe C, the safety-link 43 is swung back out of closure-forming position and the handles 40 rocked outwardly to retract the rollers 38. The ring gear 14 is rotated to line up the throat 10 and slot 27 and the device A pushed axially 45 around the pipe C, so that the latter is located more or less centrally within the opening 28 of the chuck 26 against the rear roller 38. The handles 40 are then swung back and the other rollers 38 brought to bear against the pipe C. Since the springs 41 are substantially equal in strength, they will balance each other and hold the device A in substantially concentric alignment with the pipe C. The safety-link 43 may then be swung across the slot 27 and secured in closed position by the wing screw 44.

It is, of course, understood that as the pipe or casing C is pulled upwardly, the air motor is operatively driven so as to rotate the brushes b either in a clockwise or counterclockwise direction, as may be desired, and at any desired speed so as to produce a highly efficient and thorough cleaning action.

If desired, the collar or chuck 26 may readily be removed and a conventional toggle-acting tong element 44' may be substituted therefor, whereupon the device may be used as a power-driven tong for coupling and uncoupling the casing. This feature is particularly convenient since it is possible with a single tool to clean a section of casing as it is being withdrawn and then, by simple replacement of chuck elements, use the tool for coupling and uncoupling the casing, as may be desired.

It should also be noted in this connection that 75 chucks substantially similar to the above de-

scribed chuck 26, equipped with suitable brushing elements, may be designed to fit existing types of power-driven well tongs and may be substituted for the pipe gripping elements commonly used therewith.

It should be understood that changes and modifications in the form, construction, arrangement, and combination of the several parts of the power-driven pipe cleaning devices may be made and substituted for those herein shown and described without departing from the nature and principle of my invention as defined in the appended claims.

Having thus described my invention, what I claim and desire to secure by Letters Patent is:

1. A pipe cleaning and brushing tool comprising a housing, power-driven means operatively mounted in the housing, a ring gear operatively connected to the power-driven means for rotation thereby, said housing and ring gear having axially aligned concentric openings therein to provide a common passageway axially through the housing and ring gear, said housing further being provided with a radial slot extending from its outer periphery inwardly and opening into the concentric opening thereof, said ring gear also having a radial slot adapted for registration with the slot of the housing when the ring gear is brought to rest in alignment with the slot of the housing so that the ring gear and housing can be moved radially around a continuous length of pipe to bring the pipe into concentric alignment with the central openings of the ring gear and housing without disconnecting the pipe or threading it therethrough, a tubular chuck secured to and mounted co-axially in the ring gear, said chuck having a radial slot aligned with the radial slot of the ring gear for clearing the pipe to be cleaned, said chuck further being provided at spaced intervals around its circumference with radially shiftable members, spring means for biasing said members inwardly, manually operable means associated with said members for optionally holding them in outwardly shifted position, a roller rotatably mounted on the inner end of each of said members for bearing against the pipe to be cleaned, and a plurality of brushes mounted upon and extending axially downwardly from the chuck, said brushes having bristles presented radially inwardly for contactive engagement with the pipe when the latter is in operative position within the housing, said brushes being adapted for rotative movement axially around the pipe upon rotation of the ring gear.

2. A pipe cleaning and brushing tool comprising a housing, power-driven means operatively mounted in the housing, a ring gear operatively connected to the power-driven means for rotation thereby, said housing and ring gear having axially aligned concentric openings therein to provide a common passageway axially through the housing and ring gear, said housing further being provided with a radial slot extending from its outer periphery inwardly and opening into the concentric opening thereof, said ring gear also having a radial slot adapted for registration with the slot of the housing when the ring gear is brought to rest in alignment with the slot of the housing so that the ring gear and housing can be moved radially around a continuous length of pipe to bring the pipe into concentric alignment with the central openings of the ring gear and housing without disconnecting the pipe or threading it therethrough, a tubular chuck secured to and mounted co-axially in the ring gear,

said chuck having a radial slot aligned with the radial slot of the ring gear for clearing the pipe to be cleaned, said chuck further being provided at spaced intervals around its circumference with

5 radially shiftable members, spring means for biasing said members inwardly, manually operable means associated with said members for optionally holding them in outwardly shifted position, a roller rotatably mounted on the inner 10 end of each of said members for bearing against the pipe to be cleaned, and a plurality of brushes mounted upon and extending axially downwardly from the chuck, said brushes having bristles presented radially inwardly for contactive engagement with the pipe when the latter is in operative 15 position within the housing, said brushes being adapted for rotative movement axially around the pipe upon rotation of the ring gear and each being in longitudinal alignment respectively with 20 one of the rollers.

3. A pipe cleaning and brushing tool comprising a housing, power-driven means operatively mounted in the housing, a ring gear operatively connected to the power-driven means for rotation thereby, said housing and ring gear having axially aligned concentric openings therein to provide a common passageway axially through the housing and ring gear, said housing further being provided with a radial slot extending from 25 its outer periphery inwardly and opening into the concentric opening thereof, said ring gear also having a radial slot adapted for registration with the slot of the housing when the ring gear is brought to rest in alignment with the slot of the housing so that the ring gear and housing can be moved radially around a continuous length of pipe to bring the pipe into concentric alignment with the central openings of the ring gear and housing without disconnecting the pipe or threading 30 it therethrough, a tubular chuck secured to and mounted co-axially in the ring gear, said chuck having a radial slot aligned with the radial slot of the ring gear for clearing the pipe to be cleaned, said chuck further being provided at spaced intervals around its circumference with radially shiftable members, spring means for biasing said members inwardly, manually operable means associated with said members for optionally holding them in outwardly shifted position, a roller rotatably mounted on the inner 35 end of each of said members for bearing against the pipe to be cleaned, a plurality of brushes mounted at uniformly spaced intervals upon the chuck adjacent to the concentric opening thereof and having radially inwardly presented bristles for contactive engagement with the pipe when the latter is in operative position within the tool, and a toggle-acting latch pivotally mounted on the housing adjacent the radial slot and being adapted optionally to swing closurewise thereacross.

4. A pipe cleaning and brushing tool comprising a housing, power-driven means operatively mounted in the housing, a ring gear operatively connected to the power-driven means for rotation thereby, said housing and ring gear having axially aligned concentric openings therein to provide a common passageway axially through the housing and ring gear, said housing further being provided with a radial slot extending from its outer periphery inwardly and opening into the concentric opening thereof, said ring gear also having a radial slot adapted for registration with the slot of the housing when the ring gear is brought to rest in alignment with the slot of the

housing so that the ring gear and housing can be moved radially around a continuous length of pipe to bring the pipe into concentric alignment with the central openings of the ring gear and housing without disconnecting the pipe or threading it therethrough, a tubular chuck secured to and mounted co-axially in the ring gear, said chuck having a radial slot aligned with the radial slot of the ring gear for clearing the pipe to be cleaned, said chuck further being provided at spaced intervals around its circumference with radially shiftable members, spring means for biasing said members inwardly, manually operable means associated with said members for optionally holding them in outwardly shifted position, a roller rotatably mounted on the inner end of each of said members for bearing against the pipe to be cleaned, a plurality of brushes mounted at uniformly spaced intervals upon the chuck adjacent to the concentric opening thereof and having radially inwardly presented bristles for contactive engagement with the pipe when the latter is in operative position within the tool, and a toggle-acting latch pivotally mounted on the housing adjacent the radial slot and being adapted optionally to swing closurewise thereto, said brushes being adapted for limited radial adjustment inwardly and outwardly toward the concentric opening of the ring gear.

5. A pipe cleaning and brushing tool comprising a housing, power-driven means operatively mounted in the housing, a ring gear having an outwardly presented peripheral set of teeth and a bearing face disposed in spaced relation to the set of teeth, a plurality of rollers operatively mounted at spaced intervals around the interior of the housing for engagement against the bearing face of the ring gear, a pair of sprockets operatively mounted in the housing, a continuous sprocket chain operatively trained around the sprockets and operatively connected to the power-driven means for rotation thereby, said chain being engaged along a portion of its length between said sprockets with a portion of the teeth in the ring gear, said housing and ring gear having axially aligned concentric openings therein to provide a common passageway axially through the housing and ring gear, said housing further being provided with a radial slot extending from its outer periphery inwardly and opening into the concentric opening thereof, said slots being located substantially on the opposite side of the housing with respect to the location of the sprocket chain, said ring gear also having a radial slot adapted for registration with the slot of the housing when the ring gear is brought to rest in alignment with the slot of the housing so that the ring gear and housing can be moved radially around a continuous length of pipe to bring the pipe into concentric alignment with the central openings of the ring gear and housing without disconnecting the pipe or threading it therethrough, a chuck removably mounted in the ring gear and having a radial slot extending inwardly and terminating in an enlarged central opening concentric with openings of the ring gear and housing, and a plurality of axially extending brushes carried by the chuck and having bristles presented radially inwardly for contactive engagement with the pipe when the latter is in operative position within the housing, said brushes being adapted for rotative movement axially around the pipe upon rotation of the ring gear.

6. A pipe cleaning and brushing tool compris-

ing a housing, power-driven means operatively mounted in the housing, a ring gear having an outwardly presented peripheral set of teeth and a bearing face disposed in spaced relation to the set of teeth, a plurality of rollers operatively mounted at spaced intervals around the interior of the housing for engagement against the bearing face of the ring gear, a pair of sprockets operatively mounted in the housing, a continuous sprocket chain operatively trained around the sprockets and operatively connected to the power-driven means for rotation thereby, said chain being engaged along a portion of its length between said sprockets with a portion of the teeth in the ring gear, said housing and ring gear having axially aligned concentric openings therein to provide a common passageway axially through the housing and ring gear, said housing further being provided with a radial slot extending from its outer periphery inwardly and opening into the concentric opening thereof, said slots being located substantially on the opposite side of the housing with respect to the location of the sprocket chain, said ring gear also having a radial slot adapted for registration with the slot of the housing when the ring gear is brought to rest in alignment with the slot of the housing so that the ring gear and housing can be moved radially around a continuous length of pipe to bring the pipe into concentric alignment with the central openings of the ring gear and housing without disconnecting the pipe or threading it therethrough, a chuck removably mounted in the ring gear and having a radial slot extending inwardly and terminating in an enlarged central opening concentric with openings of the ring gear and housing, a plurality of axially extending brushes carried by the chuck and having bristles presented radially inwardly for contactive engagement with the pipe when the latter is in operative position within the housing, said brushes being adapted for rotative movement axially around the pipe upon rotation of the ring gear, and a plurality of rollers carried by the chuck for stabilizing engagement with the pipe during rotation of the chuck.

7. A pipe cleaning and brushing tool comprising a housing, power-driven means operatively mounted in the housing, a ring gear having an outwardly presented peripheral set of teeth and a bearing face disposed in spaced relation to the set of teeth, a plurality of rollers operatively mounted at spaced intervals around the interior of the housing for engagement against the bearing face of the ring gear, a pair of sprockets operatively mounted in the housing, a continuous sprocket chain operatively trained around the sprockets and operatively connected to the power-driven means for rotation thereby, said chain being engaged along a portion of its length between said sprockets with a portion of the teeth in the ring gear, said housing and ring gear having axially aligned concentric openings therein to provide a common passageway axially through the housing and ring gear, said housing further being provided with a radial slot extending from its outer periphery inwardly and opening into the concentric opening thereof, said slots being located substantially on the opposite side of the housing with respect to the location of the sprocket chain, said ring gear also having a radial slot adapted for registration with the slot of the housing when the ring gear is brought to rest in alignment with the slot of the housing so that the ring gear and housing can be moved

75

radially around a continuous length of pipe to bring the pipe into concentric alignment with the central openings of the ring gear and housing without disconnecting the pipe or threading it therethrough, a chuck removably mounted in the ring gear and having a radial slot extending inwardly and terminating in an enlarged central opening concentric with openings of the ring gear and housing, a plurality of axially extending brushes carried by the chuck and having bristles presented radially inwardly for contactive engagement with the pipe when the latter is in operative position within the housing, said brushes being adapted for rotative movement axially around the pipe upon rotation of the ring gear, and a plurality of spring-pressed rollers carried by the chuck for stabilizing engagement with the pipe during rotation of the chuck.

8. A pipe cleaning and brushing tool comprising a housing, power-driven means operatively mounted in the housing, a ring gear having an outwardly presented peripheral set of teeth and a bearing face disposed in spaced relation to the set of teeth, a plurality of rollers operatively mounted at spaced intervals around the interior of the housing for engagement against the bearing face of the ring gear, a pair of sprockets operatively mounted in the housing, a continuous sprocket chain operatively trained around the sprockets and operatively connected to the power-driven means for rotation thereby, said chain being engaged along a portion of its length between said sprockets with a portion of the teeth in the ring gear, said housing and ring gear having axially aligned concentric openings therein to provide a common passageway axially through the housing and ring gear, said housing further being provided with a radial slot extending from its outer periphery inwardly and opening into the concentric opening thereof, said slot being located substantially on the opposite side of the housing with respect to the location of the

sprocket chain, said ring gear also having a radial slot adapted for registration with the slot of the housing when the ring gear is brought to rest in alignment with the slot of the housing so that the ring gear and housing can be moved radially around a continuous length of pipe to bring the pipe into concentric alignment with the central openings of the ring gear and housing without disconnecting the pipe or threading it therethrough, a chuck removably mounted in the ring gear and having a radial slot extending inwardly and terminating in an enlarged central opening concentric with openings of the ring gear and housing, a plurality of axially extending brushes carried by the chuck and having bristles presented radially inwardly for contactive engagement with the pipe when the latter is in operative position within the housing, said brushes being adapted for rotative movement axially around the pipe upon rotation of the ring gear, a plurality of spring-pressed rollers carried by the chuck for stabilizing engagement with the pipe during rotation of the chuck, and means associated with at least some of the rollers for optionally withdrawing them from operative position.
